UNITED STATES PATENT OFFICE.

JOSEPH HOFFMAN, OF NEW YORK, N. Y., ASSIGNOR TO JOSEPH RECKENDORFER, OF SAME PLACE.

LEAD AND CRAYON HOLDER.

SPECIFICATION forming part of Letters Patent No. 250,537, dated December 6, 1881.

Application filed October 11, 1881. (No model.)

To all whom it may concern:

Be it known that I, JOSEPH HOFFMAN, of the city, county, and State of New York, have invented certain new and useful Improvements 5 in Lead and Crayon Holders, of which the following is a specification.

My invention relates to that kind of lead and crayon holder known as the "automatic"—a holder in which the lead clamp or grasping 10 device is brought to a position in which it takes hold of the lead by a spring and is actuated against the stress of the spring by a longitudinally-movable pressure-cap to release the lead.

15 The holder in which my improvement is comprised consists of a sheath, in whose tip is formed one or more holes, intended to permit the entrance therein at proper times of one or more knots or projections on the expanding 20 lead grasping or clamping jaw or jaws carried by the lead-tube. The latter placed within the handle has a rotary movement only, and has a projecting guide-pin, which enters both a circular guide-slot in the handle and also an inclined slot in a pressure-cap arranged to move 25 longitudinally in the handle. Within the cap is a spring, which forces the cap back in the direction to rotate the lead-tube far enough to bring the protuberances on the lead-clamping 30 jaws out of register with the holes in the sheath tip or nozzle, and the cap can by hand be pressed forward against the stress of the spring to cause the lead-tube to rotate far enough to bring the protuberances on the clamping-jaws in 35 register with the holes in the sheath-tip, thus permitting the jaws to expand and release the lead. When hand-pressure on the cap is removed the retracting-spring returns the parts to a position in which the lead-clamp closes.

40 In the accompanying drawings, Figure 1 is a side elevation, partly in section, of a holder embodying my invention, the tip section being on line 1 1, Fig. 5. Fig. 2 is a longitudinal section of the tip and the lead-tube, with the 45 jaws in register with openings in the tip, the section being on line 2 2, Fig. 6. Fig. 3 is a side elevation of the rear end of the sheath. Fig. 4 is a like elevation of the pressure-cap. Fig. 5 is cross-section on enlarged scale on line 5 5, Fig. 1. Fig. 6 is a section on enlarged

scale on line 6 6, Fig. 2. Fig. 7 is a section on enlarged scale on line 7 7, Fig. 1.

A is the tubular sheath or handle, provided with a tip or nozzle, *a*, as usual. B is the lead-containing tube, suitably supported within the 55 sheath, and connected therewith by a pin, *b*, which projects from it into a circular slot, *c*, in a ferrule fixed on the rear end of the sheath, this pin-and-slot connection permitting the tube a movement of partial rotation, but preventing it from moving longitudinally with respect to the sheath. The front end of the lead-tube carries one or more clamping-jaws—in this instance two spring-jaws, *d*, which extend to within a short distance of the front end of 60 the sheath tip or nozzle *a*, and normally stand apart. Upon the outer face of each jaw is formed a small knob or protuberance, *e*, and in the tip are formed holes *f*, at such distance apart as to register with the knobs *e*. When 65 the tube B is rotated far enough in one direction the knobs *e* will be brought opposite the holes *f*, and they consequently, by the expansive action of the jaws, will rise and enter therein, and so permit the jaws to release the 70 lead, as indicated in Figs. 2, 6. When, on the other hand, the tube is rotated far enough to throw the knobs *e* out of register with holes *f*, the knobs will be carried under and pressed by the imperforate portions of the tip, and the 75 jaws consequently will be pressed together upon the lead, as indicated in Figs. 1, 5. To provide for obtaining these movements of the lead-tube, I mount upon the sheath A a pressure-cap, C, connected with the sheath by a pin and 80 longitudinal slot connection, *g* *h*, which permits the cap to move back and forth lengthwise of the sheath. In the cap is also formed a spiral or inclined slot, *i*, which is entered by the pin 85 *b* of the lead-tube. The slot *i* is so placed that 90 when the cap is moved forward it will rotate the lead-tube in a direction to carry the knobs *e* into register with holes *f*, and so release the lead, and when moved back it will rotate the tube in the opposite direction, thus carrying the knobs *e* out of register with holes *f*, and consequently closing the lead-clamping device. The rearward movement of the cap is effected 95 automatically by the retracting-spring *j*, confined between the end of the sheath and the 100

head of the pressure-cap, and the forward movement of the cap is effected by hand against the stress of the retracting-spring.

The holder thus made is simple, effective, 5 and automatic in action.

What I claim, and desire to secure by Letters Patent, is—

A lead and crayon holder composed of the tubular sheath, longitudinally-movable pressure-cap, and retracting-spring, in combination 10 with the rotary lead-tube, united by pin-and-slot connection with the sheath and pressure-cap, substantially as described, the lead-clamping

jaws carried by the tube, and provided with knobs or protuberances *e*, and the sheath tip or 15 nozzle provided with holes *f*, with which the protuberances *e* are thrown into and out of register, in the manner and for the purposes set forth.

In testimony whereof I have hereunto set 20 my hand.

JOSEPH HOFFMAN.
